UNITED STATES PATENT OFFICE.

ELI LEHMAN, OF MARTINSVILLE, ILLINOIS.

DESIGN FOR A HEEL-PLATE.

SPECIFICATION forming part of Design No. 29,453, dated October 4, 1898.

Application filed June 4, 1898. Serial No. 682,608. Term of patent 14 years.

To all whom it may concern:

Be it known that I, ELI LEHMAN, a citizen of the United States, residing at Martinsville, in the county of Clark and State of Illinois, 5 have invented and produced a new and original Design for Heel-Plates, of which the following is a specification, reference being had to the accompanying drawings, forming a part thereof, in which—

- o Figure 1 represents a perspective view of a heel-plate constructed according to my design. Fig. 2 is a cross-section on the line xx of Fig. 1, the same extending through two of the screw-openings therein.
- 5 My invention consists of the design for a heel-plate made the subject of the illustration

in the accompanying drawings. As shown in said drawings, the plate 1 has its outer edge cut upon a convex curve and its inner edge scalloped, as shown at 2, the sides of the plate 20 converging from its outer edge inwardly.

Having now described my invention, what I claim is—

The design for a heel-plate, substantially as shown and described. 25

In testimony whereof I affix my signature in the presence of two witnesses.

ELI LEHMAN.
